LOOSE-LEAF BOOK CONSTRUCTION

Murray Vernon, New York, N. Y., assignor to S. E. & M. Vernon, Inc., New York, N. Y., a corporation of New York

Application January 23, 1943, Serial No. 473,405

7 Claims. (Cl. 129—23)

This invention relates generally to loose leaf binders and more particularly to loose leaf binder construction which, while possessing the desired properties of permitting pages to be inserted, withdrawn, or changed in position is easily and economically fabricated of non-critical materials.

Among the principal objects of the present invention lies the provision of loose leaf note book construction in which no metal parts need be used.

Another object herein lies in the provision of structure of the class described in which the rings may be independently operated by a simple manual motion either to an "open" position (when sheets may be inserted or withdrawn), or to a "closed" position in which, barring rupture of the sheets themselves the sheets are securely retained in position in the book.

A still further object of the present invention lies in the provision of a loose leaf note book of the ring binder type of construction in which a kind of "snap" action is obtained without the use of springs as such.

A feature of the invention lies in the simple low cost manufacture thereof so that the same may have a consequent wide sale and distribution.

A further feature of the present invention lies in the fact that the support element and rings are operable as a unit independently of the cover of the note book so that the notebook may be composed of any desired material.

These objects and other incidental ends and advantages will more fully appear in the progress of this disclosure and be pointed out in the appended claims.

In the drawing similar reference characters indicate corresponding parts throughout the several views of the embodiment, which is shown.

Figure 1 is a view in perspective of an embodiment of the invention.

Figure 2 is an enlarged sectional view of Figure 1 as seen from the plane 2—2 on Figure 1. In this view the bottom ring has been removed.

Figure 3 is an elevational view, partly in section as seen from the left of Figure 2.

Figure 4 is a sectional view of the support element as seen from the plane 4—4 on Figure 2.

Figure 5 is a sectional view of the support element as seen from the plane 5—5 on Figure 2.

Figure 6 is an enlarged sectional fragmentary view as seen from the plane 6—6 on Figure 2.

Figure 7 is a view taken generally similarly to

Figure 6 but shows the parts in an altered position thereof.

Figure 8 is a view taken generally similarly to Figure 7 but shows the parts in a further altered position thereof.

Turning now to the embodiment of the invention as illustrated in Figures 1 to 8 inclusive, the device generally indicated by numeral 20 includes a front cover 21, a rear cover 22, a rear member or saddle 23, a support element 24 and rings 25, only one of which is shown.

The covers 21 and 22 and the rear member or saddle 23 may be of any suitable construction well known in the art, such as stiff cardboard covered by cloth, artificial leather, and so forth. The covers 21 and 22 are thus hingedly connected to the rear member 23 along the hinged portions 27 and 28. While in the illustration in the drawing of an embodiment of the invention the device is illustrated as having two rings, it will be obvious to those skilled in the art to which the present invention relates that any desired number of rings may be used in any desired interspacing.

The rear member 23 is preferably slightly curved to produce a convex outer surface 29 and a concave inner or forward surface 30. The degree of concavity of the surface 30 preferably substantially conforms to the convexity of the rear or inner surface 31 of the support element 24. The support element 24 is preferably fabricated of any suitable material such as a strip of hard wood and the front or normally exposed surface thereof indicated by numeral 32 is preferably of convex configuration. The support element 24 is preferably not as long as the rear member 23.

The support element 24 is provided with a plurality of channels, 33, as many channels as there are rings. The channels are of uniform construction which is best seen in Figures 4 and 6 to 8 inclusive. By reason of the fact that the channels 33 are of uniform construction, a detailed description of one will suffice for all. A channel 33 has side walls 34 and 35, an angular top wall 36 having an apex or projection 39, and sloping bottom walls 37 and 38. The side walls 34 and 35, of the channel 33 support the ring in a substantially upright position, that is to say, perpendicular to the surface 32 of the support element 24. The sloping bottom walls 37 and 38 support the ring underneath the same while the upper surface of the enclosed portion of the ring is supported by the top wall 36 at and adjacent

40

to apex 39 as will be more fully described hereinbelow.

One method of forming the channel 33 contemplates the placing in the support element 24 of a pair of juxtaposed bores 50 and 51 (see Figure 4). These bores are preferably placed by the use of suitable jigs and in the embodiment shown they are placed substantially at 25° with relation to the horizontal. The drill used is preferably slightly greater in diameter than the cross section of the ring, and the intersection of these two bores produces a desired configuration including the various walls and the projections previously described.

The support element 24 and the rear member 23 are fixedly secured together at any time during the fabrication of the device 20, by any suitable means such as for example, the rivets 52 which engage suitable aligned orifices 40 and 41 in the rear member 23 and the support element 24 respectively.

The rings 25 are substantially identical and therefore a description of one will suffice for all. A ring 25 includes a sheet carrying portion 42 and a retainer portion 43. The ring 25 is preferably of uniform curvature lying along the circumference of a true circle. For the purposes of this description the sheet carrying portion is generally considered as that visible in Figures 2 and 3, while the retainer portion is that disposed within the confines of the support element in Figure 6. Thus the ends of the sheet carrying portion 42 run into the adjoining ends of the retainer portion. The retainer portion 43 is preferably split transversely and medially to form the ring terminals 46 and 47. The ring terminals are preferably rounded or in the shape of a squat cone or spaced from each other. Such construction is for the purpose of forming an indentation in the retainer portion 43 for the purpose of engaging the apex or projection 39. This result may be accomplished either by spacing the terminals 46 and 47 or by rounding them, or giving them a conical configuration, or by both spacing and rounding.

The ring itself is preferably composed of a resilient material as, for example, cellulose acetate. Obviously the ring may be composed of other materials as thermoplastic or thermosetting plastics which are well known. The ring may be molded in the shape shown or it may be formed up under heat and pressure in suitable dies and/or jigs.

Since the rings are composed of resilient material the terminals thereof may be temporarily separated sufficiently, so that they may be inserted within the entrances to the channel 33.

Operation

As presently understood the operation of the device 20 is substantially as follows. The rings are preferably constructed so that at any point they are of substantially uniform cross section. As may be seen from a perusal of the drawing, the channel 33 is of irregular configuration, though the configuration is symmetrical on either side of the central longitudinal axis of the support element 24. By reason of the apex or projection 39 the effect of a constriction in the center of the channel is produced, or at least the apex or projection extends into the otherwise unobstructed circular path of travel of the ring when rotated. This obstruction finds a dead center position of rest when it projects downwardly between the terminals 46 and 47 of the ring 25.

The last described position of the ring is seen in Figure 6. In this position the exposed part of the ring sheet carrying portion 42 is continuous and obviously, orificed sheets such as the sheet 60 cannot be removed without damaging the sheet. Movement of the ring 25 either clockwise or counter-clockwise is inhibited by the deformity, recess or depression of the ring disposed between the terminals 46 and 47, as previously described. In order for such clockwise or counter-clockwise rotation to occur the terminal 47 or the terminal 46 must be moved past the projection 39. This passage beyond the projection will require flexure of the portions of the ring adjacent the particular terminals thereof. A preferred method of causing rotation lies in first applying lateral pressure in the direction of the arrow A on Figure 6, assuming that the rotation is to be in a counter-clockwise direction. This movement causes the terminal 46 to flex downwardly slightly and enables it to pass the projection 39 in the direction of the arrow A'. The terminal of the ring thus assumes a less curvilinear position thereof, on Figure 7.

As the terminal of the ring passes the projection a certain snapping action is felt and the ring will take the position shown in Figure 7. The ring may then be rotated in the direction of arrows B and B' on Figures 6 and 7 respectively through substantially 180° so that the ring will take a position shown in Figure 8. This portion of rotation, after the flexing has occurred, is relatively free but may be inhibited by a slight frictional rubbing upon the ring of the projection 39 and the bottom walls 37 and 38. This friction may be adjusted by slightly relieving the clearances involved.

When the ring is in the position indicated by the full lines on Figure 8, it becomes a relatively simple matter to separate the terminals 46 and 47 to the dot-dash position there shown. This separation is accomplished by moving the exposed ring portions in the directions of the arrows C and D.

After the desired sheets have been removed or replaced, the reversal of the position of the ring 25 from that shown in Figure 8 to that shown in Figure 6 requires a reversal of the previously described steps, or more particularly, the mere rotation through substantially 180° in the direction of either the arrow C or the arrow D.

In the hereinabove described embodiment of the invention, resiliency of certain of the parts is desirable for convenient operation. While the resiliency of the ring 25 permits proper operation a slightly easier operation is obtained when the parts of the support element are slightly resilient, especially the projection 39 and the bottom walls 37 and 38. I have found that the support element performs satisfactorily when composed of wood and where desired the bearing surfaces within the channels may be lubricated with wax.

It may thus be seen that I have provided novel and useful loose-leaf notebook binder constructions which are efficient in use and economical in manufacture.

I wish it to be understood that I do not desire to be limited to the exact details of construction shown and described, for obvious modifications will occur to a person skilled in the art.

I claim:

1. A loose-leaf book for use with orificed sheets, comprising a support element having a channel; a stationary projection in said channel; a resilient ring including a sheet carrying portion and a

retainer portion which is discontinuous; said resilient ring being movably disposed within said channel and having a depression adapted to be engaged by said stationary projection; said resilient ring being distortable sufficiently to pass around said projection as the ring is annularly rotated.

2. A loose-leaf binder construction for use with a plurality of orificed sheets, comprising: a resilient ring including a sheet carrying portion and a retainer portion which is discontinuous, forming ring terminals; a ring carrying channel through which said ring may have continuous annular movement, said ring having a predetermined normal path of travel; a projection having an angularly arranged face disposed within the channel and fixed in position with relation thereto, said projection extending into said path of travel of said ring and being engageable between said ring terminals; said resilient ring flexing out of its normal annular path of travel to pass said projection; said angularly arranged face being adapted to be engaged by one of said terminals so that the flexure of the ring thereby requires a reduced rotating force.

3. A loose-leaf book binder construction for use with a plurality of orificed sheets, comprising: a resilient ring including a sheet carrying portion and a retainer portion which is discontinuous forming a pair of ring terminals; a ring carrying channel through which said ring may have continuous annular movement, said ring having a predetermined normal path of travel; a wedge shaped projection disposed within the channel and fixed in position with relation thereto, said projection having a pair of oppositely disposed and angularly arranged faces extending into the normal path of travel of said ring and being engageable between said ring terminals; said resilient ring being distortable out of its normal annular path of travel to pass said projection; one of said angularly arranged faces being adapted to engage one of said terminals and the other of said angularly arranged faces being adapted to engage the other of said terminals; whereby rotation of the resilient ring in its normal path of travel will cause one of the angularly arranged faces to move one of the terminals out of its normal path of travel by a wedging action.

4. A loose-leaf book construction for use with a plurality of orificed sheets, comprising: a resilient ring including a sheet carrying portion and a discontinuous retainer portion having a pair of independent terminals; said ring having means forming a depression thereon in the retainer portion thereof; a channel within which the ring is annularly movable; said channel hav-

ing means forming a projection alternately engageable or disengageable within said depression as the ring is moved; said projection acting to inhibit movement of the ring through said channel when the projection is in engagement with said depression; said resilient ring being temporarily distortable as it flexes to pass around the projection; said terminals being temporarily separable from each other for placing or removing 10 said sheets on or off said ring by flexure of said resilient ring.

5. A loose-leaf book for use with orificed sheets, comprising: a support element having a channel; a stationary projection in said channel; 15 a resilient ring including a sheet carrying portion and a retainer portion which is discontinuous; said ring having a pair of oppositely disposed terminals each having an angular surface; said resilient ring being movably disposed 20 within said channel, said terminals being adapted to engage said projection; whereby annular movement of said ring in said channel will cause the projection to coat with one of the angular surfaces to deflect the terminal upon which it is 25 disposed and thereby distort the ring so that it may pass the obstruction formed by the said projection.

6. A loose-leaf book construction for use with orificed sheets, comprising: a support element 30 having a channel which is formed by a pair of juxtaposed intersecting bores axially disaligned, the portion of said support element disposed at the intersection of said bores forming a stationary projection in said channel; a resilient ring 35 including a sheet carrying portion and a retainer portion; said resilient ring being movably disposed within said channel and having a depression adapted to be engaged by said projection; said resilient ring being sufficiently flexible to 40 enable it to be temporarily distorted so that it may pass around said projection as the ring is annularly rotated.

7. A loose-leaf book for use with orificed sheets, comprising: a support element having a channel; a stationary projection in said channel, said projection having an angular face; a resilient ring including a sheet carrying portion and a retainer portion which is discontinuous forming 45 a pair of terminals each having rounded end; said resilient ring being movably disposed in said channel; one of said terminals having the rounded end thereof adapted to coat with the angular face on said projection so as to deflect the flexible ring so that it may pass by 50 said projection.

MURRAY VERNON.
